CLAIM

The ornamental design for an over door organizer, as shown and described.

DESCRIPTION

FIG. 1 is a front, right and top perspective view of an over door organizer, showing my new design;

FIG. 2 is a rear, left and bottom perspective view thereof;

FIG. 3 is a front view thereof;

FIG. 4 is a rear view thereof;

Fig. 5 is a left side view thereof;

FIG. 6 is a right side view thereof;

FIG. 7 is an enlarged top plan view thereof;

FIG. 8 is an enlarged bottom plan view thereof;

FIG. 9 is a rear, left and bottom perspective view of the design in a detached status;

FIG. 10 is a front, right and top perspective view of the design in a detached status;

FIG. 11 is an enlarged view of portion 11 shown in FIG. 1;

FIG. 12 is an enlarged view of portion 12 shown in FIG. 9;

FIG. 13 is an enlarged view of portion 13 shown in FIG. 10;

and,

FIG. 14 is a front view of the stand of the over door organizer.

The evenly dashed broken lines shown in the drawings illustrate portions of the over door organizer that form no part of the claimed design. The unevenly dashed broken lines show the boundaries of the detail views that form no part of the claimed design.

1 Claim, 14 Drawing Sheets
